UNITED STATES PATENT OFFICE.

HAROLD R. RANKEN, OF PHILADELPHIA, PENNSYLVANIA, ASSIGNOR TO THE LEEDS & NORTHUP COMPANY, A CORPORATION OF PENNSYLVANIA.

TEMPERATURE-INDICATING DEVICE FOR RUBBER-TREATING APPARATUS.

1,264,681.

Specification of Letters Patent. Patented Apr. 30, 1918.

Application filed July 17, 1914. Serial No. 851,666.

To all whom it may concern:

Be it known that I, HAROLD R. RANKEN, a citizen of the United States, residing in the city of Philadelphia, county of Philadelphia, State of Pennsylvania, have invented certain new and useful Improvements in Temperature-Indicating Devices for Rubber-Treating Apparatus, of which the following is a full, clear, and exact disclosure.

This invention relates to the manufacture of rubber, more particularly to the installation of electrical resistance thermometers in rubber treating apparatus, and has for its object to provide a junction or inlet box for passing the lead wires of the portable bulb through the wall of the rubber treating vessel without permitting leakage and without any effects from thermo-electric action; to provide an insulation for the lead wires inside the treating vessel that will promote flexing of the lead wires and will be unaffected by conditions inside the treating vessel; and to provide a protective flexible tubing for the wires inside the vessel that will prevent leakage into the wires, bulb or inlet box.

The successful operation of electric resistance thermometers depends upon the maintenance of good electrical insulation over the system and upon the absence of poor or leaky joints. In connection with rubber treating apparatus such as vulcanizers, box kilns, etc., wherein a fluid, gas, or liquid is used under high or low temperature and under induced pressure, atmospheric pressure or vacuum, great difficulty has been experienced in insulating the joint of the portable bulb lead wires through the wall of the treating vessel, making the same fluid, gas, liquid, and pressure tight, and preventing thermo-electric action at the joint. The present invention obviates this difficulty by the provision of a novel inlet box which conducts the lead wires without breaks or joints into the treating vessel through insulated passageways so sealed as to be liquid, gas, fluid, and pressure tight.

Difficulty has also been experienced in so insulating the lead wires within the vessel that the insulation will not break down owing to conditions within the vessel, and will not obstruct the ready flexing of the wires. The present invention obviates this

difficulty by insulating the flexible lead wires from each other by glass beads which promote the easy flexing of the wires and are unaffected by heat, chemical, or other changes within the vessel.

Difficulty has also been experienced in preventing short-circuiting, and in preventing obstruction to the proper operation of the thermometer owing to the ingress of fluids, especially steam, gas and liquids to the wires, bulb and inlet box. The present invention obviates this difficulty by inclosing the lead wires inside the vessel with a protective flexible tubing which is liquid, gas and fluid tight, and is so sealed to the box and bulb as to positively prevent leakage into these parts.

In the drawing, one form of apparatus that may be used to practice my invention is shown, in which drawing:

Figure 1 is a fragmentary view showing the application of my invention;

Fig. 2 is a diagrammatic view showing the electrical connections of the thermometer;

Fig. 3 is a detail sectional view of one of the box connectors;

Fig. 4 is a detail sectional view of the inside flexible lead.

For the purposes of illustration, a vulcanizer 10 is shown equipped with an electrical resistance thermometer embodying my improvements, but it is to be understood that the application of the invention is not limited to vulcanizing apparatus, as in its broadest aspect the invention contemplates the effective installation of an electrical resistance thermometer having a portable bulb upon or in any containing apparatus for a treating medium or agent for rubber in any stage of its manufacture.

The electrical resistance thermometer used in the present embodiment is of the usual and well known type comprising a modified Wheatstone bridge indicating instrument 11, a sensitive bulb 12, the resistance changes of which are recorded by the indicating instrument in the usual manner, and three lead wires 13 electrically connecting the indicating instrument with the bulb, as shown diagrammatically in Fig. 2.

In carrying out my invention the three lead wires 13 from the indicating instrument are passed into the vulcanizer through an inlet box 14 which will be presently de-

scribed, then continued inside the vulcanizer for any desired distance and terminally equipped with the thermometer bulb 12, two of the wires being connected 5 with one end of the resistance coil of the bulb and the third with the other end of the coil. The connections of the lead wires are such that one of them is in circuit with the battery and the other in circuit with the 10 resistance ratio arms R_1, R_2 of the indicator, so that the effect of the length or temperature of the lead wires upon the temperature reading is *nil*. These long lead wires inside the vulcanizer permit of the bulb being 15 readily manipulated and placed at any desired location in the vessel where an indication of the temperature is desired.

The inlet box 14 comprises a base member 15 and a cap member 16, which with packing washers 17 between them, are clamped tightly together by bolts 18. The base member 15 is provided with a threaded nipple 19 which is screwed into a threaded opening formed in the wall of the vulcanizer, the 25 threads being leaded or otherwise treated to seal and make the connection fluid, gas, liquid, and pressure tight.

There are three box connectors disposed in the cap members 16 to form insulated 30 passageways for the three lead wires 13, one of which connectors is shown in detail in Fig. 3. Each connector comprises a metal tube 20, preferably brass, which is insulated from the cap member by a tube 21 of insulating material, preferably glass, and is threaded at both ends to receive nuts 22 that are screwed down and compress washers 23 of insulating material, preferably mica, tight 35 against the cap member to seal and make 40 the passage of both tubes through the member fluid, gas, liquid, and pressure tight. The corresponding lead wire 13, preferably formed of nickel alloy, passes without breaks or joints from the indicating instrument 11 45 through the brass tube 20 to the bulb 12, and is soldered, cemented, or otherwise sealed as shown at 24, to both ends of the tube to prevent leakage around the wire through 50 the tube.

By virtue of the lead wires passing into the vulcanizer without breaks or joints, thermo-electric action with consequent disturbance of the balance of the Wheatstone bridge cannot occur as would be the case 55 were the inside and outside lead wires soldered or otherwise joined together by a bond of different metal from the wires.

The three lead wires outside the vulcanizer from the indicator to the inlet box are 60 incased in a protective covering 25 of any preferred construction, and the three lead wires inside the vulcanizer from the inlet box to the bulb are incased in a flexible metal tube 26, of fluid, gas, liquid, and pressure 65 tight construction, such as shown for in-

stance in detail in Fig. 4. The covering 25 and tube 26 are anchored fast to respective caps 27 and 28 to prevent flexing with consequent breaking off of the lead wires at the ends of the box connectors. 70

To enhance flexibility without disturbing the insulation of the lead wires inside the vulcanizer, beads 29 of insulating material, preferably glass, are threaded upon the wires and insulate them from each other and from their protective flexible tube. The lead wires thus insulated, may be made of any desired length to permit of manipulating and localizing the bulb at any desired point in the vulcanizer without danger of breaking down the insulation due to the increased wear thereupon. Furthermore, the glass beads are unaffected by heat, chemical, or other changes within the vulcanizer. 80

To prevent leakage into the bulb, inside 85 lead wires, and inlet box, the ends of the flexible metal tube 26 are soldered or otherwise sealed to the bulb and inlet box, as shown at 30 and 31.

From the above description, it will be 90 seen that both the vulcanizer and the thermometer will perform their functions undisturbed, since leaking at the joints of the lead wires through the wall of the vulcanizer cannot occur, leakage into the inside 95 lead wires, bulb, or inlet box cannot occur, thermo-electric action cannot occur, and the breaking down of the insulation of the inside lead wires cannot occur.

Having thus described this form of my 100 invention, what I claim and desire to protect by Letters Patent is:

1. In an apparatus of the kind described in combination, a chamber, means to heat the interior of the chamber, a fluid-tight inlet-member providing access to the interior of the chamber, an electrically controlled indicator, a conductor-member passing through said inlet-member and an electric heat-sensitive member connected to said conductor-member within said chamber at a point beyond said inlet-member. 105

2. In an apparatus of the kind described in combination, a chamber, means to heat the interior of the chamber, a fluid-tight inlet-member providing access to the interior of said chamber, an electrically controlled temperature indicator, a flexible conductor member passing through said inlet-member and an electric heat-sensitive member 110 connected to said conductor-member within said chamber at a point beyond said inlet-member. 115

3. In an apparatus of the kind described in combination, a chamber, means to heat the interior of the chamber, a box secured to said chamber and provided with a conduit to permit the passage of wires therethrough to the interior of the chamber, an electrically controlled temperature indicator, 125

conducting wires passing through the ori-
fice of said box and having their outer ter-
minals connected to said indicator and an
electric thermometer bulb connected to the
5 wires within the chamber at a point beyond
the box.

4. In an apparatus of the kind described
in combination, a chamber, a fluid-tight in-
let-member provided with a conduit adapted
10 to permit the passage of the conductor mem-
ber therethrough into the interior of the
chamber, an electrically controlled tempera-
ture indicator, a conductor-member passing
15 through said conduit, and having its outer
end connected to said indicator, an electric
heat-sensitive member connected to said con-
ductor-member within said chamber at a
point beyond said inlet-member and a fluid-
20 tight joint between said conductor and the
walls of the conduit in said inlet-member.

5. The combination of a chamber for treat-
ing rubber, means to heat the interior of the
chamber, a portable electric resistance ther-
mometer bulb inside the chamber, a tem-
25 perature indicator outside the chamber, con-
ductor wires electrically connecting the bulb
to the indicator, an inlet box conducting the
wires with their continuity uninterrupted
leakage tight through the wall of the cham-
30 ber, a protective tubing housing the wires

inside the chamber extending beyond the
inlet-box, and means anchoring the outer end
of the tubing stationary to the box and pre-
venting flexing of the lead wires at their
entry into the box.

35

6. The combination of a chamber for treat-
ing rubber, means to heat the interior of
the chamber, a portable electric resistance
thermometer bulb inside the chamber, a tem-
perature indicator outside the chamber, con-
40 ductor wires electrically connecting the bulb
to the indicator and forming a flexible lead
for the portable bulb inside the chamber,
an inlet box conducting the wires with their
continuity uninterrupted leakage tight 45
through the wall of the chamber, a leakage
tight flexible tubing extending beyond the
inlet box housing the wires inside the cham-
ber and sealed to the box and to the bulb
and preventing leakage into the box, bulb, 50
and wires, and beads of heat- and chemical-
impervious insulating material threaded
upon the wires inside the tubing.

Signed at Philada., county of Philada.
and State of Pennsylvania, this ninth day 55
of July, 1914.

HAROLD R. RANKEN.
